UNITED STATES PATENT OFFICE

2,405,823

CONTAINER

Paul C. Gaylord, New Brighton, N. Y., assignor to
 Greif Bros. Cooperage Corporation, Cleveland,
 Ohio, a corporation of Delaware

Application October 8, 1943, Serial No. 505,423

4 Claims. (Cl. 229—5.5)

1

My invention relates to containers and more particularly to that type of containers having fibrous cylindrical bodies in laminated form and metal closures for the top and bottom.

The objects of my invention, among other things, are to provide an improved sealing joint for the open ends of the container when the metal closures or covers are applied and secured, more particularly to the top of the container, whereby the head cover may be affixed firmly in place while providing a tight sealing joint around the container rim; also to provide an improved seal or gasket construction that dispenses with the use of a binding agent or adhesive, and at the same time reinforces the rim portion or margin of the open end of the laminated fibrous container, which is of advantage when the metal closure or cover is inserted in the open end and forced into sealing position on the slightly yielding fibrous body in the zone of the gasket where effective and uniform sealing is important.

A further object of my invention is to provide a compressible gasket secured to the outer walls of the body slightly below the rim of the open end of the container, and so arranged that when the rim margin of the fibrous body is curved outwardly and over the gasket as the metal closure is applied to the container, the compression of the curved rim margin and gasket will afford a tight and uniform seal to prevent leakage of the contents of the container, and at the same time the compressed gasket affords a fixed circular support so as to secure the metal cover or closure firmly in place within the rim of the container by having the cover clamping devices bear against the under side of the gasket.

Other advantages of my invention will be set forth in the following description taken in connection with the drawing.

In the accompanying drawing showing preferred embodiments of my invention:

Fig. 1 is a side elevation of the container body with the cover in superposed position;

Fig. 2 is an enlarged section on the line 2—2 of Fig. 1;

Fig. 3 is an enlarged fragmentary elevation showing the cover in sealing position;

Fig. 4 is a detail sectional view of parts shown in Fig. 3;

Fig. 5 is a section on the line 5—5 of Fig. 2;

Fig. 6 is fragmentary elevation of a modified form of cover and attaching ring therefor;

Fig. 7 is section on the line 7—7 of Fig. 6; and

Fig. 8 is a detail section on the line 8—8 of Fig. 6.

2

Similar numerals refer to similar parts throughout the several figures.

Referring to Figs. 1—5, the cylindrical body 9 of the container is preferably made of fibrous material in laminated or multi-layer form with the lower edge of the bottom portion closed by the seam 10 in any suitable manner. Around the outside of top portion of the body 9 slightly below the rim edge 11, the circular seal or gasket 12, preferably made of compressible material such as twisted paper rope, is secured by the continuous line stitching 13 passing through the body. Other types of securing means may be used, but I prefer the continuous line of stitching 13 as shown in Fig. 5, which enables the gasket 12 to be slightly compressed without injuring or loosening the stitching. This annular line of stitching 13, while holding the gasket 12 firmly in place also reinforces the margin of the body at 14 where the rim edge 11 is slightly flared outwardly as shown in Fig. 2 for the insertion of the metal closure or cover 15 which fits into the open end of the container body 9 as shown in Fig. 3.

The cover 15 shown in Figs. 1—3 is the well-known closure for containers of the lug type having the slotted lugs 16 arranged in spaced-apart relation around the circumference of the cover 15. The cover 15 has the central countersunk panel 17 which merges in the annular vertical wall 18 that fits snugly against the inner wall of the body 9 (Fig. 3) when the cover 15 is applied to the body. This annular wall 18 merges with the curved wall 19 from which the lugs 16 depend so as to form an inverted U-shaped channel 20 adapted to fit over and enclose the rim of the body 9 and the gasket 12 (Figs. 2 and 3). When the cover 15 is forced downwardly into the body. The lugs 16 are then bent inwardly by the closing tool (not shown) with their end portions 21 bearing against the outer walls of the body 9. The lugs 16 also press upwardly against the under side of the gasket 12, and the channel 20 curves outwardly the flared rim edge 11 from the position shown in Fig. 2 to that shown in Figs. 3 and 4 so as to form a tight seal on the open end of the body 9 as the cover 15 and lugs 16 curl outwardly and compress the rim edge 11 around the upper side of the gasket 12; at the same time the lug ends 21 apply pressure beneath the gasket 12 which also acts to hold the lugs 16 in place. The stitching 13 reinforces the body margin 14 below the rim edge 11, and also serves as an annular hinge for the rim edge 11 when outwardly flared and also during the subsequent curling of such rim edge 11 over the gasket 12 as shown in Fig. 3.

The lug ends 21 also bear upwardly against the under side of the gasket 12 which affords a yielding abutment for the lug ends 21.

In Figs. 6-8, I have shown a modified form of cover and attaching ring therefor. In this modified form the cover 15 has the central panel 17 and vertical annular wall 18 with channel 22 that is semi-circular in cross-section as shown in Fig. 8. The attaching ring 23 is of the usual construction that fits snugly over the cover channel 22, and has its ends formed with transversely-disposed clips 24 and 25. The clips 24 and 25 have holes bored in alinement through which the threaded bolt 26 passes with the nut 27 screwed on the threaded bolt 26 as shown in Figs. 6 and 7. When the clips 24 and 25 are drawn toward each other by the bolt 26 and nut 27 in clamping the ring 23 to the cover 15, the cover channel 22 and ring 23 curl outwardly the rim edge 11 and squeeze this rim edge 11 and gasket 12 together to provide a tight seal, the gasket 12 also serving to hold the ring 23 in proper horizontal alinement while securing the cover 15 in place.

Other types of cover closures may be used to effect the same advantageous result in securing an effective seal by bending over the flared rim edge 11 and compressing same along with the gasket 12 to provide a tight and uniform sealing for the closure extending around the open end of the container.

Various changes in the form, construction and disposition of the parts may be made without departing from the scope of my invention or sacrificing its advantages in use.

I claim as my invention:

1. In a container having a fibrous laminated body with an open end, a compressible gasket of twisted fibrous material fastened by stitching to the outer wall of the body slightly below and in mutual parallelism with the rim edge of said open end.

2. In a container having a fibrous laminated body with an open end, a compressible gasket of twisted paper rope fastened by a continuous line

of stitching passing through said gasket and outer wall of the body slightly below and in mutual parallelism with the rim edge of said open end.

5. 3. A container comprising a fibrous laminated cylindrical body having an open end outwardly flared around its margin, a metal closure having a counter-sunk center portion fitted snugly within, and also having a rim portion overlapping, 10 said open end, and an annular gasket of compressible material fastened permanently to the body by stitching passing through the entire wall thereof substantially along the base of the flared margin and mutually parallel with its rim edge and also adapted to be compressed in a plurality of directions by the closure rim between the body, flared margin and closure when the latter is forced into sealing position, said rim portion of the closure also curling and compressing said 15 flared margin over said gasket outwardly on the annular hinge formed by the stitching and also compressing the gasket inwardly and upwardly against the body and curled flared margin.

4. A container comprising a fibrous laminated cylindrical body having an open end outwardly flared around its margin, a metal closure having a counter-sunk center portion the sidewalls of which fit snugly within said open end with an outer curved wall rim portion overlapping the 20 flared margin of the body, an annular gasket of fibrous material more compressible than the body fastened permanently to the body by stitching passing through the entire wall thereof substantially along the base of the flared margin, and 25 means for positively locking the closure to the open end, thereby causing its outer rim portion to be bent inwardly to forcibly compress the gasket in a plurality of directions against the body and flared margin and also to curl said flared 30 margin outwardly on the line of said stitching between the gasket and said outer rim portion while compressing same against the gasket when the closure is locked in sealing position.

PAUL C. GAYLORD.
